United States Patent Office

Des. 186,126
Patented Sept. 15, 1959

186,126

SPOON

Lyle V. Burford, Rolling Hills, Calif., assignor to Royal Pacific Company, Inc., Los Angeles, Calif., a corporation of California

Application May 18, 1959, Serial No. 55,947

Term of patent 7 years

(Cl. D44—29)

Fig. 1 is a perspective view of the spoon showing my new design;

Fig. 2 is a top plan view thereof;

Fig. 3 is a side elevation thereof;

Fig. 4 is a top plan view of Figure 3; and,

Fig. 5 is a bottom plan view of Figure 3.

I claim:

The ornamental design for a spoon, substantially as shown.
